his Attorney.

UNITED STATES PATENT OFFICE.

GEORGE A. KEHL, OF ST. PAUL, MINNESOTA.

SAND TOY.

Application filed December 10, 1921. Serial No. 521,354.

To all whom it may concern:

Be it known that I, GEORGE A. KEHL, a citizen of the United States, residing at St. Paul, in the county of Ramsey and State 5 of Minnesota, have invented certain new and useful Improvements in Sand Toys, of which the following is a specification.

This invention relates to toys adapted to be actuated by a granular medium, such as 10 sand, or by rice, wheat and the like, an object of the invention, being the provision in a toy of this class, of feed adjustment means, whereby either of these mediums may be successfully employed without the 15 necessity of, in any way, adjusting the parts which are animated by the falling medium.

Another object of the invention is to provide, in a toy of the class described, a discharge chute which is normally pivotally 20 suspended in equilibrium at a point just above its center of gravity, and in a manner to be thus held by the head of sand at the mouth of the sand container, a feature of the invention being the novel construction 25 of the pivotal mounting of the chute, whereby a slight disturbance of the equilibrium of the latter, will cause the head of sand to fall out of symmetry relative to the chute body.

30 Other objects of the invention will be pointed out throughout the specification, the invention consisting in the construction, combination and arrangement of parts hereinafter described and claimed.

35 In the accompanying drawings:

Figure 1, is a perspective view of a sand toy embodying my invention.

Figure 2, is a fragmentary side view of the sand container, the discharge chute and 40 one bucket shown in their normal positions.

Figure 3, is a perspective view of the beam support.

Figure 4, is a vertical sectional view on line 4—4 of Figure 2, partly broken away, 45 and drawn to a reduced scale.

Figure 5, is a vertical sectional view on line 5—5 of Fig. 4.

Figure 6, is a fragmentary side view of the sand container showing the manner of 50 connecting the uprights to the container.

Figure 7, is a fragmentary perspective view of the tie piece connecting a pair of legs, and

55 Figure 8, is a perspective view of one of the trip levers on the discharge chute.

The present invention is an improvement

upon the sand toy which is the subject of my application for Letters Patent now pending and filed May 2nd, 1921, Serial No. 465,973, 60 patented August 15, 1922, No. 1,425,865 and comprises a container 1, shaped like an inverted hollow cone, the upper circular edge thereof being formed with an out-turned surrounding bead 2, and its conic wall being pressed outward at four equidistant 65 points adjacent the bead 2, to form sleeves 3, which latter radiate to the center of the container in parallelism with the conic wall thereof. Frictionally fitting each of said sleeves, and abutting endwise against the bead 2, is the leg 4, the upper end thereof being bent to the angularity of the container to render the shank 4 of all the legs parallel to a position approximately 70 midway of their length. Below the parallel portions, the legs flare outwardly, to afford a greater base area to lend stability to the toy.

The legs are connected in pairs by the cross strap 5, at the base of the parallel leg 80 portions, and is formed with an outstanding flat tongue 6 adapted to be projected through the elongated eye 7, in the down-turned lugs 8, at the respective outer ends 85 of the beam support 9.

The support is formed of a flat strip of uniform width and is bent downward midway between the lugs 8, to form a vertically disposed guide way 10, of parallel width, with flat inner walls, said walls being 90 perforated with horizontally and oppositely disposed laterally alined slots 11, adapted to receive the pivot pin 12, which latter rotatably fits in the slots and is bodily slidable therein. The pin extends through the 95 center of the beam 13, and is secured therein, said beam fitting flatwise in the guide way 10, to freely move therein when it is rocked upon its pivot. The beam is bowed upwardly symmetrically about the pivot pin, 100 and has horizontally disposed forks 14, pivotally carrying respectively the buckets 15. A cord 16 restricts the swinging movement of the respective buckets, in their downward movement, whereby the buckets are 105 sufficiently tilted to discharge their cargo, as shown in Figure 1.

The apex of the inverted hollow cone, constituting the container, is cut off to form a true circular discharge opening 17. Directly above said discharge opening is rotatably mounted the throttle valve 18, by 110

means of the stem 19 which extends rotatably transversely through and beyond opposite walls of the container. At opposite ends said stem extends through horizontally aligned arched openings 20, in the respective outwardly and upwardly inclined side walls 21 of the discharge chute 22.

This discharge chute is formed with a straight smooth bottom 23, which in connection with the sides 21, forms a trough suspended in equilibrium on the pin 19, the latter engaging tangentially the circular upper edge 24 of the openings 20.

I have found the curvature of the edge 24, which is shown full size in Figure 2, to operate very efficiently as will hereinafter be explained.

Secured on the under side of the chute, and in exact symmetry thereon, and extending longitudinally one on either side of the center thereof, are the tripping arms 25. The arms are preferably formed of wire, and have contact terminals 25' bent downwardly to match the angularity of the sides 25 of the tapered buckets 15, as is best shown in Figure 2, wherein the bucket is shown in the position at which it initially contacts with the arm, as distinguished from the position shown in Figure 1, wherein the equilibrium of the chute has been disturbed, causing the latter to slide to one side, as by means of its arched edge on the stem 19, as is also shown in dotted lines in Figure 2. The contact terminals are formed of wire 35 of relatively small diameter, and are crimped in a manner to produce a plurality of vertically disposed parallel rails 26 forming a miniature open work frame.

I have found that this type of structure, namely, vertical small round wires, offers a minimum resistance to the striking buckets, and facilitates upward sliding of the latter over the knee *a* (Fig. 2) to the position shown in dotted lines. I have tried tin plate terminals, but found the frictional resistance too great to properly tilt the chute.

The journals of the stem 19 fit sufficiently tight, to hold the throttle valve 18 at any desired position to which it may be turned, a suitable handle for that purpose being shown.

Obviously, when the rice or wheat is placed in the container the throttle may be positioned as shown in Figure 5, thereby affording greater clearance for the kernels to pass. When sand is to be used, the throttle may be set horizontally, thereby throttling the discharge opening and restricting the flow, to prevent the buckets from filling too quickly.

Normally, the sand or other actuating medium, will accumulate in a symmetrical heap in the center of the chute, until it seals the discharge opening 17. As the sand 65 is evenly distributed, the chute is held per-

fectly balanced on the stem 19, as shown in Fig. 5.

In operation, I have found when the loaded bucket descends and the empty bucket strikes with considerable force against the terminal 25', the beam 13 rebounds more or less thereby delaying the bucket in its journey to its ultimate position. To obviate this, I have mounted the beam pivot 12, in slotted holes 11, which permits the beam to slide laterally when the empty bucket hits the tripping arm. This is an important feature, inasmuch as the rebound of the bucket, permits the sand from the chute to fall outside the bucket.

As hereinbefore stated, the top of the legs frictionally engage the eyes 3, so that a fairly firm connection with the container is secured. The two pairs of legs are thus positioned and then sprung toward each other as indicated at the bottom of the legs by dotted lines in Figure 1. When thus sprung, the beam support carrying the beam is placed over the tie members 5, and the tongues 6 projected through the openings 7, the stress of the spring in the legs, sufficing to hold the structure assembled. This novel knockdown construction renders the toy commercially practical, as any ordinary person can assemble it, and a relatively small 95 carton is required, to contain it.

As shown in Figure 1, the cover of the box is used as a sand bin, and also assists in holding the legs in normal position.

I claim:

1. In a sand toy of the class described, the combination with the sand container, said container having an opening in the bottom thereof, of a trough open at the ends disposed symmetrically directly beneath said opening and spaced therefrom, tripping arms carried by said trough, horizontally disposed oblong openings, one in each side wall of the trough midway between the ends thereof, said openings being on a level and aligned at right angles to the trough, a pin supported by the container and extending through said openings, each of said openings having an arched upper edge for the purpose set forth.

2. In a sand toy of the class described, the combination with the sand container, said container having an opening in the bottom thereof, of a trough open at the ends, disposed symmetrically directly beneath said openings, and spaced therefrom, downwardly and outwardly extending similar tripping arms carried by said trough, one for each end thereof, and a loose pivotal connection including a pivot, between the trough and container for normally suspending said trough in horizontal position on the container, said connection including means whereby the pivot thereof is enabled to shift from its normal position.

3. In a sand toy of the class described, the

combination with the sand container, said container having an opening in the bottom thereof, of a trough open at the ends, and having tripping arms, said trough disposed 5 symmetrically directly beneath said opening and spaced therefrom, a loose pivotal connection between the trough and container for normally suspending said trough in horizontal position and rendering the trough 10 bodily swingable, and a throttle valve adjacently directly above said opening in the path of the sand in the container and means extending to the outside of the container for operating said throttle valve for the purpose 15 set forth.

4. A sand toy comprising a frame, a container at the top of the frame having an opening in the bottom thereof, a trough open at the ends and having tripping arms, said 20 trough pivotally suspended symmetrically directly beneath said opening and swingable in a vertical plane, a beam having pivotal support midway of its ends on the frame to render it swingable upwardly, and buckets 25 pivotally carried at the respective ends of said beam, and adapted to engage respectively said tripping arms to tilt said trough when said beam is actuated, said pivotal support for said beam including a pivot pin mounted 30 to slide horizontally in the frame.

5. A sand toy comprising a frame, a sand container having an opening in the bottom thereof positioned at the top of the frame, a chute open at its ends suspended symmetri-

cally in a horizontal position on said container directly beneath said opening and spaced therefrom, said chute carrying tripping arms, a beam, buckets pivotally carried one at each end of the beam, and a slideable pivotal support for said beam midway of the ends thereof whereby, when said beam is actuated to cause the buckets to strike against said tripping arms to tilt said trough, said slideable pivotal connection will yield laterally to permit said beam to bodily move, for the 45 purpose set forth.

6. In a sand toy structure for a sand toy having a frame, a container with an opening in its bottom, at the top of the frame, chute mechanism swingingly suspended beneath said opening and having tripping arms, and sand conveying devices, including buckets swingable alternately into engagement with said tripping arms to actuate said chute mechanism and thereby load the respective buckets said structure comprising sleeves on the outside of said container, two long wire legs, each leg formed of two leg members joined by a cross tie, with a projecting tongue intermediate its ends, each leg frictionally 50 projectable into said sleeves so as to stand parallel relative to each other, and apertures in a part of said conveying devices to receive said tongues under stress of the spring in 55 said wire legs as and for the purpose set forth.

In testimony whereof I affix my signature.
GEORGE A. KEHL.
